2 Sheets-Sheet 2

UNITED STATES PATENT OFFICE

JOHN H. VINCENT, OF KALAMAZOO, MICHIGAN, ASSIGNOR TO WESTERN TABLET & STATIONERY CORPORATION, OF DAYTON, OHIO, A CORPORATION OF OHIO

DRIER FOR PRINTED SHEETS AND THE LIKE

Application filed May 15, 1930. Serial No. 452,593.

The main objects of this invention are:

First, to provide a drier for printed sheets which is of large capacity and at the same time compact and simple in structure.

Second, to provide a drier of the class described which may be readily coupled or associated with a printing machine and which is automatic in operation.

Objects pertaining to details and economies of construction and operation of my invention will definitely appear from the description to follow. The invention is defined in the claims.

A structure embodying the features of my invention is clearly illustrated in the accompanying drawings, in which:

Fig. 1 is a fragmentary side elevation of my improved drying machine or apparatus, a fragment only of the printing machine being illustrated.

Fig. 2 is a fragmentary plan view partially in section on line 2-2 of Fig. 1.

Fig. 3 is a perspective view of one of the conveyor links with its carrier.

Fig. 4 is a fragmentary section of the conveyor.

Fig. 5 is a side elevation of the apparatus provided with a housing for certain parts.

In the accompanying drawings 1 represents a fragment of a printing machine and 2 a moving part thereof. My improved drying apparatus comprises a frame consisting of the upright members 3, 4 and 5 suitably braced and connected to support the moving parts, and the horizontal bed members 6 which are mounted on the upright members 3 and 4.

On the bed members 6 I mount a feed way consisting of the members 7, 8 and 9 arranged in spaced pairs to receive the plunger 10 which is reciprocatingly mounted on the way 11. On these uprights I mount opposed way members 12 and 13 preferably of angle iron and disposed in opposed spaced pairs, the pairs of way members being downwardly inclined. The horizontally disposed way members 14 extend between the lower ends of the way members 12 and 13.

These way members are arranged in a triangular relation with conveyor supporting

and guide rollers 15, 16 and 17 disposed at the angles thereof. The roller 17 is the driving roller of the conveyor, its shaft 18 having a ratchet wheel 19 at one end thereof. This ratchet wheel is driven through the pawl 20 carried by the rocker 21 oscillatingly mounted on the shaft 18 at the inside of the ratchet wheel. This rocker is connected to the arm 22 on the rockshaft 23 by means of the link 24.

The rockshaft is operatively connected to the moving member 2 of the printing machine through the lever 25 pivoted at 26 and connected to the member 2 by the link 27 and to the arm 28 on the rockshaft 23 by the link 29. The rockshaft 23 has an arm 30 with a segmental slot 31 therein to receive the bolt 32 on the adjustable arm 33. This adjustable arm is connected by the link 34 to the lever 35 pivoted at 36 and connected by the link 37 to the plunger. Thus the plunger is driven in synchronism with the conveyor which has a step by step movement, owing to its ratchet driving means. The link 34 also has an adjustable connection to the lever 35 as indicated so that the stroke of the plunger may be considerably varied.

The conveyor chain is made up of a plurality of links 38 having spaced rigid arms 39 to which the carrier fingers 40 are secured. 80 These fingers are formed of wire and are of considerable spread so as to effectively hold sheets of considerable size. By the term "sheets" I contemplate cards and the like.

As the sheets are delivered by the plunger 85 they are pushed through the guide members 8 and thereby centered relative to the carriers, a sheet being indicated by dotted lines at 41, Fig. 2. The feed way is arranged in a plane radial to the toothed roller 17 so that 90 the sheets are effectively delivered to be picked up by the carrier fingers or flights which pass through openings 42 in the feed way.

The sheets are carried up by the forward 95 reach of the conveyor, passing over the roller 15 at which point they are shifted from one flight to the preceding flight, then carried down the rear reach of the conveyor and discharged to the guide chute 43, which is ar- 100

ranged in opposed relation to the roller 16. This chute has a curve supporting the sheets until they are properly directed to the inclined portion 44 and therefrom on to the discharge conveyor 45.

In Fig. 5 I show the rear reach of the conveyor as embodied with a housing 46 to which a blower or suction means may be attached at 47. I have found, however, that this is not required under ordinary working conditions.

The drier is of large capacity and holds the sheets in separated relation until the ink is sufficiently dry so they are not likely to offset.

I have illustrated my improvements in an embodiment which I have found very satisfactory. I have not attempted to illustrate or describe other modifications or adaptations which I contemplate as I believe this disclosure will enable those skilled in the art to embody or adapt the same as may be desired.

Having thus described my invention what I claim as new and desire to secure by Letters Patent is:

1. In an apparatus of the class described, the combination of an upright drying conveyor comprising conveyor way members disposed in triangular relation, a conveyor comprising a plurality of carrier links having carriers formed of wire projecting therefrom, supporting rollers for said conveyor disposed at the angles of said way members whereby the conveyor travels in supporting engagement with said way members, a ratchet driving means for one of said rollers, a feed way disposed in a plane radial of said driven roller, said feed way being provided with an opening to permit the passage of said carriers and with a centering guide, a reciprocating feed plunger operatively associated with said feed way and synchronized with said conveyor driving means, a discharge conveyor disposed below said driving conveyor, and a guide chute disposed opposite the lower rear supporting roller to coact with the edges of the sheets as they are carried around said lower rear conveyor supporting roller and guide the same to said discharge conveyor.

2. In an apparatus of the class described, the combination of an upright drying conveyor comprising conveyor way members disposed in triangular relation, a conveyor comprising a plurality of carrier links having carriers formed of wire projecting therefrom, supporting rollers for said conveyor disposed at the angles of said way members whereby the conveyor travels in supporting engagement with said way members, a ratchet driving means for one of said rollers, a feed way disposed in a plane radial of said driven roller, said feed way being provided with an opening to permit the passage of said carriers and with a centering chute, and a reciprocating feed plunger operatively associated

with said feed way and synchronized with said conveyor driving means.

3. In an apparatus of the class described, the combination of an upright drying conveyor comprising conveyor way members disposed in triangular relation, a conveyor comprising a plurality of carrier links having carriers formed of wire projecting therefrom, supporting rollers for said conveyor disposed at the angles of said way members whereby the conveyor travels in supporting engagement with said way members, a ratchet driving means for one of said rollers, a friction brake operatively associated with said driven roller, a feed way disposed in a plane radial of said driven roller, said feed way being provided with an opening to permit the passage of said carriers and with a centering guide, and a reciprocating feed plunger operatively associated with said feed way and synchronized with said conveyor driving means.

4. In an apparatus of the class described, the combination of an upright drying conveyor comprising conveyor way members disposed in triangular relation, a conveyor comprising a plurality of carrier links having carriers projecting therefrom, supporting rollers for said conveyor disposed at the angles of said way members whereby the conveyor travels in supporting engagement with said way members, means for driving said conveyor step by step, a feed way provided with an opening to permit the passage of said carriers, a feed plunger operatively associated with said feed way and synchronized with said conveyor driving means, a discharge conveyor disposed below said driving conveyor, and a guide chute disposed opposite the lower rear supporting roller to coact with the edges of the sheets as they are carried around said lower rear conveyor supporting roller and guide the same to said discharge conveyor.

5. In an apparatus of the class described, the combination of an upright drying conveyor comprising conveyor way members disposed in triangular relation, a conveyor comprising a plurality of carrier links having carriers projecting therefrom, supporting rollers for said conveyor disposed at the angles of said way members whereby the conveyor travels in supporting engagement with said way members, means for driving said conveyor step by step, a feed way provided with an opening to permit the passage of said carriers, and a feed plunger operatively associated with said feed way and synchronized with said conveyor driving means.

6. In an apparatus of the class described, the combination of an upright conveyor comprising a conveyor way, a conveyor provided with a plurality of skeleton carriers projecting from said way, supporting rollers for said conveyor, said conveyor travelling in

supporting engagement with said way, a preceding carrier, said links being in supporting engagement with said way members. In witness whereof I have hereunto set my hand.

5 supporting engagement with said way members.

ment, and a feed plunger operatively associated with said feed way and synchronized with said conveyor driving means.

7. In an apparatus of the class described, the combination of an upright conveyor comprising conveyor way members disposed in a downwardly diverging relation, a conveyor supporting roller disposed at the top of said way members, supporting rollers disposed at the lower ends of said way members, a conveyor comprising a plurality of carrier links having spaced rigid arms thereon and carriers mounted on said arms, said links being in supporting engagement with said way members and coupled so that as they travel over the roller at the upper ends of said way members the sheets are delivered from one carrier to the preceding carrier.

8. In an apparatus of the class described, the combination of an upright conveyor comprising conveyor way members disposed in a downwardly diverging relation, a conveyor supporting roller disposed at the top of said way members, supporting rollers disposed at the lower ends of said way members, and a conveyor comprising a plurality of carrier links traveling in supporting engagement with said way members and having spaced rigid arms thereon and carriers mounted on said arms, said carrier links being coupled so that as they travel over the roller at the upper ends of said way members the sheets are delivered from one carrier to the preceding carrier.

9. In an apparatus of the class described, the combination of an upright conveyor comprising conveyor way members disposed in a downwardly diverging relation, a conveyor supporting roller disposed at the top of said way members, supporting rollers disposed at the lower ends of said way members, a conveyor provided with a plurality of carriers spaced so that as they travel over the roller at the upper ends of said way members the sheets are delivered from one carrier to the preceding carrier, said links being in supporting engagement with said way members, means for driving said conveyor with a step by step movement, and feed means synchronized with said conveyor.

55 10. In an apparatus of the class described, the combination of an upright conveyor comprising conveyor way members disposed in a downwardly diverging relation, a conveyor supporting roller disposed at the top of said way members, supporting rollers disposed at the lower ends of said way members, a conveyor provided with a plurality of carriers spaced so that as they travel over the roller at the upper ends of said way members the sheets are delivered from one carrier to the
